UNITED STATES PATENT OFFICE.

ALVA LOWERY, OF ASTORIA, OREGON.

ROPE CLIMBING AND SUPPORTING DEVICE.

Application filed November 13, 1922. Serial No. 600,674.

To all whom it may concern:

Be it known that I, ALVA LOWERY, a citizen of the United States, residing at Astoria, in the county of Clatsop and State of Oregon, have invented certain new and useful Improvements in a Rope Climbing and Supporting Device, of which the following is a specification.

This invention relates to improvements in rope climbing and supporting devices.

The primary object of this invention is the provision of a device which will find its most general use in connection with rope or cable climbing, and by means of which a person may readily mount or demount the cable or rope, in safety, and without the necessity of exerting manual effort.

A further object of this invention is the provision of a practical type of climbing device for rope cables, whereby an economic and effective arrangement is provided, which may be utilized in connection with the scaling of stacks, elevators, high buildings, and other places ordinarily inaccessible, except in conjunction with a compact climbing arrangement.

A further object of this invention is the provision of a climbing device for ropes, which is adapted for stirrup carriage upon the legs of a user, so that the user may readily ascend or descend a cable, rope, or other device of like character.

Other objects and advantages of this invention will be apparent during the following detailed description.

In the accompanying drawings, forming a part of this specification, and wherein similar reference characters designate corresponding parts throughout the several views,

Figure 1 is a perspective view, showing the manner in which a person may utilize the improved climbers in connection with the scaling of a stack or similar construction.

Figure 2 is a perspective view of an improved rope climbing stirrup.

Figure 3 is a cross sectional view, showing certain cooperating details of this invention.

Figure 4 is an inside view of the improved rope climbing device.

Figure 5 is a cross sectional view, taken substantially on the line 5—5 of Figure 3 with the ankle engaging strap omitted.

Figure 6 is a side elevation of the rope clamping portion of this invention, showing the same in position to permit movement along a rope or cable.

Figure 7 is a side elevation, showing the improved clamping arrangement embodied in this invention in secure engagement with a rope.

Figure 8 is a cross sectional view, showing the manner in which certain jaw elements of the clamping arrangement embodied in this invention are serrated to cooperate with the strands of a rope or cable.

Figure 9 is a cross sectional view, taken through cooperating jaw elements embodied in this invention, showing the intermeshing and cooperating relation of the same.

Figure 10 is a transverse cross sectional view, taken substantially on the line 10—10 of Figure 7.

Figure 11 is a perspective view of a plate supporting element embodied in this invention.

Figure 12 is a front perspective view of the manner in which the improved device is carried by the foot and leg of a user, and showing the manner in which the same cooperates with a rope or cable.

In the drawings, wherein for the purpose of illustration is shown but the preferred embodiment of this invention, the letter A designates a rope or other supporting device, such as a cable, with which the improved devices B are adapted for use in connection with a climbing operation.

Referring to the rope A, the same may be of any approved construction or arrangement.

In the majority of instances, this rope A may be the ordinary manila rope or steel cable, formed of a plurality of braided or spirally wound strands of material.

Referring to the device B, a pair of the same are used in connection with a climbing operation; a person strapping or otherwise affixing a device B to each of his legs, as will be more specifically set forth hereinafter, and substantially as is illustrated in Figure 1 of the drawings. Each device B preferably includes an L-shaped stirrup frame 20, which may be of steel or any approved material, including the upstanding leg portion 21, which is preferably offset, as at 22, intermediate its ends to conform to the inside ankle bone of the user. The foot engaging portion 23 of the stirrup frame 20 is disposed substantially at right angle to the leg portion 21, and is outturned, at 24, upon its ends; the end portion 25 being provided with a transverse apertur

25 therein, which oscillatively and adjustably receives a link 26 of substantially triangular formation. The upper end of the stirrup leg 21 is provided with a staple or 5 loop member 27, which provides a transverse opening or slot 28 upon the outside surface of the leg portion 21, and within which a leg strapping arrangement 29 cooperates, as will be subsequently described.

10 A supporting plate 35 is preferably provided for cooperation with the stirrup frame 20, having a transverse opening 36 in the lower portion thereof, which rotatably receives the smooth bearing surface 38 of a 15 bolt or rivet member 39. This member 39 is adapted for screw threaded engagement within a screw threaded socket 40, which is formed inwardly of the foot engaging portion 23 from the outside surface of the 20 frame 20, substantially as is illustrated in Figure 3 of the drawings. A loop portion 41 is preferably provided adjacent the upper edge of the plate 35, extending inwardly of the inside surface 42 of the same, and 25 providing a slot or opening 44 which slidably receives the leg portion 21 of the frame 20 therethrough, so that said supporting plate 35 may be mounted upon the outside of the frame 20 adjacent the lower end thereof, being oscillatively supported by the enlarged bearing end of the bolt 39, and limited in its oscillation by contact of the edges of the leg portion 21 with the ends of the slot 44.

30 Clamping jaws 47 and 48 are provided, which are oscillatively supported upon the outside surface 49 of the supporting plate 35, as by bolts 50, which engage through certain transverse openings 51 in the plate 35, and are retained thereon as by the 35 nuts 52.

35 The jaw elements 47 and 48 are somewhat similar in construction, each including an ear 55 which receives a bolt 50, above mentioned, so that said jaws may be oscillated. In their normal positions, the jaws 47 and 48 each include vertical portions 58, the facing cam surfaces 60 of which define a passageway therebetween, adapted to receive the 40 rope A. The facing cam surfaces 60, are eccentrically struck with respect to the axes upon which said jaws oscillate, so that as the jaws 47 and 48 are relatively oscillated upwardly on the supporting plate 35, the 45 passageway for reception of the rope A, is constricted in cross section. It can readily be understood that upon sufficient upward movement of the jaws they will be clamped to the rope A for supporting the plate 35 in a set position, all of which is incident to engagement of the cam faces 60 against the strands 15 of the supporting rope A. These cam faces 60 are serrated, to provide the shallow spiral grooves 63, within which 50 the strands 15 of the supporting cable A

are received during a clamping operation, so that there will be no liability of slipping of the clamped jaws over the rope A during a supporting operation. In order to insure synchronous movement of the jaws 47 and 48, the intermeshing teeth 67 are provided thereon, which teeth extend outwardly toward each other, immediately adjacent the outside surface 49 of the supporting plate 35, substantially as is illustrated in the cross sectional view, in Figure 9 of the drawings. It can readily be understood that by this construction, the jaws will be assured of synchronous operation, and because of the relatively large tooth 69 upon the jaw 48, the 55 relative downward movement of said jaws is fixed.

60 Intermeshing guard fingers 70 and 71 are respectively provided upon the jaws 47 and 48, which, when said jaws are clamped to a cable A, as is illustrated in Figure 7 of the drawings, extend laterally over the cable or rope to prevent any liability of lateral sliding disconnection of the device B from the cable A.

65 Referring to the manner of connecting a device B to the leg of a user, the leg portion 21 of the stirrup frame 20 is disposed vertically along the inside of the leg of the user, substantially as is illustrated in Figure 1 of the drawings. To clamp the stirrup frame 20 to the foot of the user, a strap 80 is provided, which is connected to one portion of the triangular shaped retaining ring 26. A buckle 81 is carried by the link strap portion 82, the latter also being connected to the retaining ring 26. With this construction, the free end of the strap 80 may adjustably engage the buckle 81 for strapping about the foot of the user, substantially as is illustrated in Figure 12 of the drawings, the strap 80 preferably looping about the outside surface of the frame 20.

70 A leg guard 90, preferably of some flexible leather is provided for connection to the upper end of the stirrup leg 21. This guard 90 may be riveted, as at 91, intermediate its ends to the leg 21. The upper portion of the guard 90 may be provided with the guard loops 92 and 93, conveniently slotted therein. In conjunction with these loop portions 92 and 93, and the staple 27, of the stirrup frame 20, a strap 95 may be provided, which is adapted for threading through the opening 28 of the staple 27, and for threading through the loops 92 and 93, so that the strap 95 may encircle the leg of the user, substantially as is illustrated in Figure 1 of the drawings, and strap the device B thereto.

75 The operation of the improved device can be readily ascertained from the cooperative positioning of the parts, as illustrated in Figures 6 to 9 inclusive. As is illustrated

in Figure 6 of the drawings, the jaws 47 and 48 are in such position that the device B may be lifted or detached or upwardly moved along the cable A, to permit the climber's ascension. When in this position, the jaws 47 and 48 are, by their weight, held in such position that the passageway between the jaws is open to permit lateral insertion of the cable therein. After the climber has so swung his leg upon which the device B is mounted, that the cable A is disposed in the passageway, and upon placing his weight upon the device B, it can readily be understood that the serrations or spiral grooves 63 in the facing cam surfaces of the jaws 47 and 48, will receive the contour of the cable strands 15, so that said cam surfaces 60 of the jaw surfaces 47 and 48 will be relatively proximately moved to tighten upon the rope A. At the same time, the fingers 70 and 71 will be laterally moved to guard against accidental disconnection of the device B from the cable A, substantially as is illustrated in Figure 7 of the drawing. In this cooperation of the clamping jaws 47 and 48, the device B will be maintained in a set position on the cable or rope A, incident to the weight of the climber, so that the climber may bear his entire weight thereon for ascending said cable A.

The importance of oscillatively mounting the plate 35 on the stirrup frame 20 is obvious, when it is considered that the flexing of the leg of the operator necessitates a sort of oscillative movement in connection with the cable A with the cooperating jaws 48 as a center. Such movement of the legs of the user does not consequently interfere with the clamping engagement of the jaws 47 or 48 with the rope or cable A. When the climber desires to lift one leg above the other, for further ascension on the cable A, it can readily be understood that by releasing his weight, and partly by upward pull, the jaws 47 and 48 will be rocked or oscillated, so that they will swing into their open position as is illustrated in Figure 6 of the drawings, whereby the device B may be laterally moved from the cable A for a further upward movement. The jaws 47 and 48 are normally maintained in their open position incident to their own weight, and in this respect, the enlarged tooth 69 operates against its cooperating jaw member 47.

From the foregoing description of this invention, it can be readily understood that an improved climbing device has been provided, which is extremely practical and will permit of the ascension of a climber with a greater degree of safety than is possible in the scaling of a ladder. The cooperating features of the jaws 47 and 48 in connection with the clamping plate 35 need not necessarily be limited to their mounting upon a

climber's stirrups, but may be used in connection with any device which it is desired to support upon the cable A. Thus, the co-operating jaws 47 and 48 have been used in connection with the supporting of a seat upon a single strand of cable A, so that a painter or other skilled laborer, may support himself in a predetermined position upon said cable, as for repairing, painting, etc.

Various changes in the shape, size and arrangement of parts, may be made in the form of invention herein shown and described, without departing from the spirit of this invention or the scope of the claims.

I claim:

1. In a device of the class described, the combination of a supporting member, jaws movably mounted upon said supporting member including cam surfaces provided with spiral serrations therein, said jaws adapted to cooperate with a rope so that the spiral serrations therein may engage the contour of the rope strands to effect a clamping operation of the jaws on the rope upon movement of the supporting member in one direction along said rope.

2. In a device of the class described, the combination of a stirrup for clamping to the leg of a user, a plate pivotally connected to said stirrup and having limited pivotal movement, and rope engaging jaws adjustable along said plate.

3. In a device of the class described, the combination of a stirrup, a plate oscillatively connected to the lower end of said stirrup, and jaws oscillatively carried by the plate.

4. In a device of the class described, the combination of a stirrup, means for mounting said stirrup upon the leg of a climber, a plate oscillatively mounted at the lower end of said stirrup upon the outside surface of the latter, means defining the amplitude of oscillation of said plate upon said stirrup, and clamping jaws outwardly carried by said plate having facing cam surfaces providing a passageway for reception of a device to be climbed.

5. In a device of the class described, the combination of a stirrup frame, means for clamping said stirrup frame to the leg of a user, a supporting plate pivotally carried at the extreme lower inside surface of said stirrup, said supporting plate having a slot upwardly therein receiving said stirrup therethrough to define the amplitude of oscillation of the supporting plate upon said stirrup, and rope climbing means movably carried by said plate.

6. In a device of the class described, the combination of a stirrup frame, means for clamping said stirrup frame to the leg of a climber, a plate oscillatively carried at the lower portion of the side of said stirrup frame, a pair of clamping jaws oscillatively

carried at the outer surface of said supporting plate each including a cam surface, means cooperating with said jaws for normally maintaining them in position so that 5 they may receive an element to be climbed, and guard means upon said jaws adapted to be moved into position upon clamping of said jaws to the element to be climbed to prevent lateral disconnection of the jaws.

10 7. In a device of the class described, the combination of a supporting frame, a plate

oscillatively carried by said frame, a pair of clamping jaws oscillatively carried by said supporting plate for movement toward and away from each other into and out of an article gripping position, and guard means upon said jaws adapted to be moved into position upon releasing of said jaws from the article to be gripped to prevent lateral disconnection of the jaws from the 15 article.

ALVA LOWERY.
